IGNITING DEVICE

Harold W. Mitton, Drummond, Mont.

Application February 28, 1933, Serial No. 193,122

1 Claim. (Cl. 67—10.1)

This invention relates to igniting devices particularly adapted for attaching to gas lanterns for lighting the same without the use of matches.

It is an object of the invention to provide an igniting device which is readily attachable to the conventional gas lantern having means for emitting sparks into the match opening of the lantern for lighting the gas burner.

A further object of the invention resides in providing a device of the above-mentioned character which is simple and durable in construction, reliable and efficient in operation, and inexpensive to manufacture.

Other objects and advantages of the invention will be apparent during the course of the following description.

In the accompanying drawing forming a part of this specification and in which like numerals are employed to designate like parts throughout the same,

Fig. 1 is a front view of the device with the wall of the casing broken away,

Fig. 2 is a vertical section taken on line 2—2 of Fig. 1,

Fig. 3 is a perspective view of one side wall showing the attaching flange, and

Fig. 4 is a view illustrating the manner of applying the device to a gas lantern.

In the drawing, wherein for the purpose of illustration I have shown a preferred embodiment of my invention, the numeral 5 denotes a casing having vertical side walls 6 and 7, a vertical front wall 8, a forwardly and downwardly inclined rear wall 9 and horizontal top wall 10. A flange 11 is formed integral with the side wall 7 and extends laterally therefrom in the plane of the top wall for attaching the casing 5 to the lamp casing, so that the opening 12 in the top wall 10 registers with the match opening of the lamp casing, as shown in Fig. 4. The flange 11 is secured to the lamp casing by a bolt 13. The side walls 6 and 7 are secured together by bolts 14 extending transversely of the casing. A shaft 15 extends transversely of the casing 5 beneath the opening 12 which is journaled in bearings 16 in the side walls and one end of the shaft extends beyond the side wall 7 with a thumb knob 17 on the end for turning the shaft. An abrasive wheel 18 is fixed on the shaft 15 within the casing with its periphery in alignment with the opening 12 in the top wall. A flint holding tube 19 extends from the rear wall 9 in a downwardly inclined direction towards the periphery of the abrasive wheel, and a flint 20 is inserted in the tube, being held in frictional contact with the periphery of

the abrasive wheel by a coil spring 21 disposed within the tube. The outer end of the tube is interiorly screw threaded to receive the thumb screw 22 which adjusts the tension of the spring 21. A pocket 23 is formed within the casing extending inwardly from the rear wall, intermediate its length, and is adapted to hold extra flints 20 which are held therein by a screw cap 24 threaded into the pocket.

In use, the igniting device is attached to the lamp casing by means of the flange 11 with the opening 12 in the top of the casing 5 in register with the match opening of the lamp casing. By quickly turning the thumb knob 17 the shaft 15 is revolved, rotating the abrasive wheel which 15 due to its frictional contact with the flint 20 in the tube 19 causes sparks to be emitted through the opening 12 and thereby ignite the lamp burner.

It is to be understood that the form of my invention herein shown and described is to be taken as a preferred example of the same, and that certain changes in the shape, size, and arrangement of the parts may be made without departing from the spirit of the invention or the scope of the subjoined claim.

Having thus described my invention, I claim:

A lighter attachment for gas lamps comprising a casing having vertical side walls, a vertical front wall, a forwardly and downwardly inclined rear wall and a horizontal top wall having an opening therein adapted to register with the match opening of the lamp casing, a lateral flange extending from one side of said casing in the plane of the top wall for securing said casing to the lamp casing, a shaft extending transversely of said casing adjacent the top wall, said shaft being journaled in the side walls of the casing with one end extending beyond the side wall, a thumb knob on the extended end of said shaft for turning the same, an abrasive wheel fixed on said shaft within said casing with its periphery in alignment with the opening in the top wall, a flint holding tube within said casing extending from the rear wall in a downwardly inclined direction towards said abrasive wheel, the inner end of said tube terminating adjacent the periphery of said wheel and the outer end opening through the rear wall to permit the insertion of the flint, a coil spring mounted in said tube to urge the flint into engagement with the abrasive wheel, and a thumb screw mounted in the outer end of said tube for adjusting the tension of said spring.
